UNITED STATES PATENT OFFICE.

EDWARD L. GILSON, OF ROSLINDALE, MASSACHUSETTS.

PRESS.

1,408,450.

Specification of Letters Patent. Patented Mar. 7, 1922.

Application filed March 6, 1920. Serial No. 363,804.

To all whom it may concern:

Be it known that I, EDWARD L. GILSON, a citizen of the United States, and a resident of Roslindale, in the county of Suffolk and State of Massachusetts, have invented an Improvement in Presses, of which the following is a specification.

This invention relates in general to mechanical presses and more particularly to a heavy duty general utility press.

An object of this invention is to provide a rugged and substantial press of inexpensive construction and of highly efficient and reliable action. Another object is to improve the construction of mechanical presses so that a wide range of application is attained and so that various grades and sizes of work are readily accommodated. Other objects will be in part obvious or in part pointed out hereinafter.

A preferred embodiment of the invention has been selected for purposes of illustration and description, and shown in the accompanying drawings wherein,

25. Figure 1 is a perspective view, and,

Figure 2 is a side elevation of a press embodying this invention.

Figure 3 is a modified form of supporting structure forming one feature of this invention.

Figure 4 is a detailed view, with certain parts broken away, showing mounting of the guiding bearings in the main frame.

Figure 5 is a detailed plan on a larger scale, with certain parts broken away, of the nut and ratchet mechanism.

Figure 6 is a cross section on line 6—6 of Figure 5 of the nut operating the screw, and,

40. Figure 7 is a plan view of one of the bearing members.

Figure 8 is an elevation in plan, and,

Figure 9 is an end view of an auxiliary nut forming part of the ratchet operating mechanism.

Referring to the drawings and more particularly Figures 1 and 2, there is shown a main frame composed preferably of steel of channel cross section and preferably consisting of a single unitary piece formed into a pair of vertical members 10 and 11 having their upper ends as 12 and 13 bent so as to be inclined toward each other. At the lower extremities of members 10 and 11 there

members 14 and 15 respectively preferably of angle iron and of sufficient lateral expanse to give the main frame and its associated parts great stability. At the extreme upper portions of the inclined sections 12 and 13 the main frame is reinforced by a pair of plates 16 and 17 securely riveted to the front and rear webs respectively of the channel frame. The vertical members 10 and 11 are braced by a horizontally extending member 18 preferably of channel section, thus forming a compression member of efficient action, the member 18 being securely riveted to the vertical members 10 and 11 as by means of right angle brackets as 19 at points substantially at the base of the angularly inclined portions 12 and 13 of the main frame. The compression member 18 of channel section is so inserted and secured that the reinforcing webs thereof extend downwardly, leaving the plane surface of the member facing upwardly.

Mounted upon the upper plane face of the compression member 18 is a bearing member 20, shown more clearly in Figure 4, suitably secured as by rivets thereto. In the apex formed by the angularly inclined sections 12 and 13 there is secured a second bearing member 21 suitably flanged and shaped to fit snugly within the apex and rigidly secured to the main frame member as by rivets or bolts. The bearing members 20 and 21 are in alignment and serve as guides for the screw 22 provided with a key-way 23 extending throughout its entire threaded length. The key-way 23 engages the key 24 suitably secured in a key-way, more clearly shown in Figure 7, in the guiding bearing 20, thereby to prevent rotation of the screw 22 while permitting a free movement within the guiding bearings 20 and 21 in a direction longitudinally of the main frame.

The screw 22 is provided with a nut 25, more clearly shown in Figures 5 and 6, resting immediately upon the upper bearing surface of the bearing 20 and there is interposed between the upper end or face of the nut 25 and the lower face of the bearing member 21 a ball or roller thrust bearing 26, the several parts being so proportioned as to fit snugly within the space between the upper and lower faces of the bearing or guiding members 20 and 21 respectively.

Referring more particularly to Figures 5

110

and 6, it will be noted that the nut 25 has a substantially cylindrical outer surface in which is cut a series of ratchet teeth 27, the outer surfaces of which in turn form the bearing surface for the operating wheel consisting preferably of the central hub 28 and the rim 29 connected thereto as by spokes 30. The hub 28 is provided with a radially extending boss 31 into the cylindrical opening 32 of which is inserted the pawl 33 having a substantially radial face 34 for engagement with a tooth 27 of the ratchet on the exterior of the nut 25 to transmit rotary movement to the nut and having a beveled surface 35 adapted to engage and ride over the teeth 27 when the hub 28 is rotated in the reverse direction. The pawl 33 is mounted upon the stem 36 provided at its outer end with a handle portion 37 for manual control or setting of the pawl 33. A spiral spring 38 surrounds the stem 36 and is interposed between the rear surface of the pawl 33 and a nut 39 of special construction screwed into the outer threaded end of the aperture 32 in the boss 31. In Figures 8 and 9 is shown more clearly the construction of the nut 39 and it will be noted that it is provided with an opening 40 forming a guiding bearing for the stem 36 and also that it is provided with a pair of diametrically opposed and axially extending slots 41 and 42 with which a pin 43 in the stem 36 engages. The diametrically opposed slots 41 and 42 also provide means for screwing the nut into place as by means of a small spanner wrench.

Referring to Figure 5, the pin 43 is shown in engagement with the slot 41 which thus securely holds the pawl 33 in the operative position shown and which therefore will permit of rotation of the nut 25 by the hub 28 in an anti-clockwise direction, the spring 38 permitting the pawl 33 to recede into the opening 32 when the hub 28 is rotated in a clockwise direction, thus imparting no rotation to the nut 25. When it is desired to cause reverse rotation of the nut 25, the pawl 33 is manually caused to recede into the opening 32 and against the spring 38 by withdrawal thereof by means of the handle 37. The pin 43 is thus withdrawn from the slot 41 whereupon the handle 37 and its associated pawl 33 may be rotated through 180° to align the pin 43 with the diametrically opposite slot 42. The handle 37 is then released, thus placing the pawl 33 in reverse relation to the ratchet teeth 27 on the nut 25.

The hub 28 may be rotated by manually grasping the rim 29 and causing a rotation thereof but in order to permit of the application of great force a lever 44 of convenient length is inserted into the lugs 45 and 46 on the hub 28 and the rim 29 respectively and in alignment with a spoke of the wheel. Suitable openings are provided in the lugs

45 and 46 to permit of the bar 44 to be conveniently and quickly inserted.

Referring more particularly to Figures 1 and 2, it will be noted that at convenient intervals in the upright members 10 and 11 there are provided bolts 47 extending through suitable apertures in the webs of the channel iron frame member and through corresponding openings in the straps 48 suitably spaced from the webs of the channel frame by the spacers 49 mounted on the bolts. When the nuts on the bolts 47 are tightened a very rigid and substantial structure results, securely fastening and holding the several parts together. The upper and lower bent ends of the straps 47 are conveniently secured to the webs as by bolts 50. The spacers 49 mounted upon the bolts 47 between the web portion of the channel frame and the strap 48 form the supports for the bars 51 and 52 bridged across the vertical members 10 and 11 upon spacers registering or corresponding in height. The bars 51 and 52 are of great depth in comparison to their thickness and together form a table for receiving the work to be operated upon by the screw 22. The spacers 49 forming the supports or bearing surfaces for the ends of the bars 51 and 52 are, by means of the bolts 47, each individually supported upon the inside end thereof by the web of the channel frame and upon the outer end thereof by the strap 48, thus offering great resistance to the downward shearing stresses imposed by the table forming members 51 and 52. The height of the members 51 and 52 is readily adjustable in that they may be readily and conveniently supported on any pair of corresponding supports throughout the range of height of the vertical members 10 and 11.

In Figure 3 is shown a modified form of supporting means for the table members 51 and 52. On the inside face of the vertical members 10 and 11 and extending upwardly in conformity with the angularly inclined sections 12 and 13 respectively, there is secured by a suitable number of rivets a supporting and reinforcing plate 53 which is of greater width than the channel frame and in the overlapping sections of which there is provided a series of vertically extending openings 54, which may be punched or otherwise made in the plate, for receiving the table members or bars 51 and 52. Such bars are thus supported on the portions 55 intervening the successive openings 54 and it will be noted that, corresponding to the supporting means heretofore described, the supporting or bearing portions 55 for the bars 51 and 52 are in themselves supported at two points, on the inside by the main portion of the plate 53 and upon the outer ends by means of the strip of metal forming the outside wall of the openings 54. Thus a sup-

port for the table members of great strength and rigidity is provided. The plate 53 extending upwardly along the inside faces of the vertical members 10 and 11 serves also to 5 greatly strengthen the upright members and also to increase the rigidity of the main frame at the bent portions thereof. A transversely extending base member as 15' is similarly secured and riveted to the upright member 10 thus reinforced by the supporting plate 53.

From the foregoing it is believed that the operation of the press structure and its associated mechanisms will be clear but by way of resumé it may be noted that the screw 15 22 is guided in its axial movement by means of the guiding bearings 20 and 21, and is prevented from rotating by means of the key-way 23 in slidable engagement with the key 24 in the bearing member 20. The nut 25 20 is rotated in either direction by means of the ratchet teeth 27 and the pawl 33 and it will be noted that the ratchet driving mechanism permits of the operation of the press within a limited space. The pitch of the thread of 25 the screw may be suitably designed so that the force manually applied to the outer end of the bar 44 may be multiplied to a great extent to exert a great downward pressure or thrust by way of the lower end of the 30 screw 22. In Figure 1 is shown the application of the press in forcing a shaft 56 into a gear 57 which is conveniently supported upon a pair of channel irons 58 placed cross-wise of the table members 51 and 52 in order 35 to support the gear 57 at points in close proximity to the hub thereof.

The downward thrust upon the work thus supported by the table members 51 and 52 is taken up or received by the supporting 40 studs or the supporting sections 55 of the reinforcing plate 52 (as shown in Figure 3), each of these supporting studs being individually supported at each end thereof. Such method of support obviates the difficulties as to stresses encountered by reason 45 of bending moments and it will be noted that the resistance to shear off the supports by the table members is doubled, permitting a corresponding increase in pressures exerted.

50 During the operation of the press the portions of the upright members 10 and 11 extending between the table members 51 and 52 and the cross brace 18 are in tension only and no stresses due to bending moments are 55 present therein. The thrust of the screw is transmitted through the nut 25 and the roller bearing 26 to the bearing 21 rigidly secured in the apex of the angularly inclined portions 12 and 13 of the frame, thus placing 60 the members 12 and 13 in tension. At the juncture of the portions 12 and 13 with the compression member 18 all horizontal components of the stresses within the members 12 and 13 are taken up in compression by the 65 compression member 18, thus effectively re-

lieving the vertical members from subjection to stresses due to bending or any tending toward distortion. It will be noted that great pressures can be actively exerted by means of the screw and nut and that by 70 means of the construction and arrangement of parts employed, the several parts are effectively freed from objectionable stresses due to bending moments.

The operating mechanism, it will be noted, 75 is housed within the space included between the apex formed by the sections 12 and 13 and the compression member 18, thus leaving a large space beneath the screw for the accommodation of various grades and sizes 80 of work. It will also be noted that the table members 51 and 52 are readily and conveniently adjustable to accommodate such varieties of work and that in the construction of the table members a convenient space 85 is left therebetween for the extension of parts operated upon by the screw.

The handle 44 is readily withdrawn from the lugs 45 and 46 on the wheel 29 so that the screw may be moved by wheel 29 in either 90 direction, by the proper adjustment of the pawl 33, at a rapid rate, thus making for great saving in time in changing the adjustment of the several parts of the mechanism. It will also be noted that structural 95 steel is employed of such dimensions and cross section that the maximum strength and rigidity is obtained with minimum of weight.

It will thus be noted there has been provided in this invention a press construction 100 in which the several objects of the invention and in which many advantages have been achieved.

As many possible embodiments of this invention may be made and as various changes might be made in the embodiment above set forth, it is to be understood that all matter herein set forth and shown in the accompanying drawings is to be interpreted as 105 110 illustrative and not in a limiting sense.

I claim:

1. In apparatus of the class described, in combination, a single member of channel section conformed into two vertical members, pressure exerting means mounted in the upper part of said conformed member, a plurality of aligned supports on said vertical members, a reinforcing member rigidly fixed to each of said vertical members to provide additional supporting means for said supports and means forming a table mounted on said supports. 115 120

2. In apparatus of the class described, in combination, a single member conformed into two vertical members, a pair of members forming a table, means mounted in the upper part of said member for exerting a thrust in a downward direction, and means forming a plurality of aligned apertures as- 125 130

sociated with each of said vertical members adapted to receive said table forming members.

3. In apparatus of the class described, in combination, a pair of vertical members, pressure exerting means mounted between the upper ends of said vertical members, a table, and a reinforcing member extending longitudinally of said vertical members, said member being provided with a series of apertures for adjustably mounting said table.

4. In apparatus of the class described, in combination, a main frame, a table adjustably mounted on said frame, a non-rotatable screw mounted in the upper part of said frame and adapted to be moved longitudinally of said frame, a nut in engagement with said screw having a ratchet formed on its outer cylindrical surface, an operating hub enclosing said outer cylindrical surface, and a pawl mounted in said hub adapted to place said hub in operative relation to said nut, and means for operating said hub.

5. In apparatus of the class described, in combination, a main frame, a table adjustably mounted on said frame, a non-rotatable screw mounted in the upper part of said frame and movable longitudinally of said frame, a nut in engagement with said screw, a thrust bearing mounted in the upper part of said frame and in engagement with said nut to receive the upward thrust therefrom, and an operating wheel co-axial with said screw, a ratchet mechanism mounted in said wheel for connecting said wheel and said nut for conjoint rotation.

6. In apparatus of the class described, in

combination, a main frame, a table adjustably mounted on said frame, a non-rotatable screw mounted in the upper part of said frame and movable longitudinally of said frame, a bearing in the upper part of said frame for guiding said screw, a nut in engagement with said screw having its outer cylindrical surface in the form of a ratchet, a thrust bearing interposed between said guiding bearing and said nut to transmit upward thrust to said main frame, an operating wheel enclosing said outer cylindrical surface of said nut and a pawl adapted to place said wheel in operative relation to said nut.

7. In apparatus of the class described, in combination, a single member formed into two vertical members and having angularly inclined upper sections forming an apex, means mounted substantially within said apex for exerting a downward thrust, a horizontally extending compression member connecting said vertical members at the base of said angularly inclined sections for freeing said vertical members from horizontal components of stress while leaving vertical components of stress within said vertical members, a plate for reinforcing each of said vertical members, said plate being provided with a series of apertures, and a table mounted in registering apertures in said plates.

In testimony whereof, I have signed my name to this specification this eighteenth day of February, 1920.

EDWARD L. GILSON.
